UNITED STATES PATENT OFFICE.

GEORGE DOUGLAS LEECHMAN, OF COVENTRY, ENGLAND.

DESIGN FOR A TANDEM-VELOCIPED FRAME.

SPECIFICATION forming part of Design No. 29,111, dated July 26, 1898.

Application filed July 31, 1897. Serial No. 646,712. Term of patent 7 years. Registered in England December 23, 1896, No. 290,727.

To all whom it may concern:

Be it known that I, GEORGE DOUGLAS LEECHMAN, a subject of the Queen of Great Britain, residing at Coventry, in the county 5 of Warwick, England, have invented and produced a new and original Design for the Frames of Tandem Velocipedes, (for which I have obtained registration in Great Britain, No. 290,727, dated December 23, 1896,) of 10 which the following is a specification, reference being had to the accompanying drawings, showing a side elevation thereof in Figure I and a perspective view in Fig. II.

The leading feature of my design consists 15 in two substantially parallel members A B, running rearward and somewhat downward from the head C. The diagonal members D and E, the back forks F and G, the front chain-stay H, and the lower backbone J are

of ordinary construction, as shown. A stay 20 K rises from the rear crank-hanger L to the top of the front diagonal member D, which it supports. The member A crosses the members D, K, and E, and in the case of a tandem bicycle the rear part A' thereof is bifurcated. 25 The said member A runs from the upper part of the head C to the rear angle M of the frame. The member B runs from the lower part of the head C to the rear crank-hanger L, crossing the front diagonal D on the way. 30

What I claim is—

The design for a tandem-velocipede frame herein shown and described.

GEORGE DOUGLAS LEECHMAN.
